UNITED STATES PATENT OFFICE.

DURBIN RICHARDSON AND CHARLES N. JACOBY, OF ROCHESTER, NEW YORK,
ASSIGNORS TO RICHARDSON CORPORATION, OF ROCHESTER, NEW YORK, A
CORPORATION OF NEW YORK.

DESIGN FOR A PORTABLE BEVERAGE-DISPENSING APPARATUS.

54,453.

Specification for Design.

Patented Feb. 10, 1920.

Application filed August 16, 1919. Serial No. 318,042. Term of patent 14 years.

To all whom it may concern:

Be it known that we, DURBIN RICHARDSON and CHARLES N. JACOBY, both of Rochester, in the county of Monroe and State of New York, have invented a new, original, and ornamental Design for a Portable Beverage-Dispensing Apparatus, of which the following is a specification, reference being had to the accompanying drawings, forming a part thereof.

Figure 1 is a side elevation, and Fig. 2 is a plan view with the top broken away.

We claim:

The ornamental design for a portable beverage dispensing apparatus, as shown.

DURBIN RICHARDSON.
CHARLES N. JACOBY.
